(57) **CLAIM**

The ornamental design for retractable trolley rails for luggage, as shown and described.

DESCRIPTION

FIG. 1 is a perspective view of the retractable trolley rails shown interconnected to a piece of luggage;

FIG. 2 is an enlarged, broken away perspective view thereof;

FIG. 3 is an enlarged, broken away perspective view of

another portion of the rail;

FIG. 4 is a reduced scale, environmental view;

FIG. 5 is a rear elevation view thereof;

FIG. 6 is a right elevation view thereof;

FIG. 7 is a top plan view thereof;

FIG. 8 is a bottom plan view thereof; and,

FIG. 9 is a left elevation view thereof.

The broken line showing of a suitcase and suitcase handle is included for the purpose of illustrating environment and forms no part of the claimed design.

The claimed design is shown enlarged and fragmented for clarity of illustration.
